UNITED STATES PATENT OFFICE.

JOSEPH SUMMER, OF PROVIDENCE, RHODE ISLAND.

DESIGN FOR AN ORNAMENTAL STOCK FOR COMBS.

42,956.

Specification for Design.

Patented Aug. 27, 1912.

Application filed May 31, 1912. Serial No. 700,849. Term of patent 7 years.

To all whom it may concern:

Be it known that I, JOSEPH SUMMER, a citizen of the United States, residing at Providence, in the county of Providence and State of Rhode Island, have invented a new, original, and ornamental Design for an Ornamental Stock for Combs, of which the following is a specification.

In the accompanying drawing which forms a part of this specification,—the figure is a front view of the ornamental stock for combs embodying my new design.

I claim:

The ornamental design for ornamental stock for combs, as shown.

JOSEPH SUMMER.
